UNITED STATES PATENT OFFICE.

HENRY L. PETERS, OF ST. LOUIS, MISSOURI.

WINDOW-SCREEN.

SPECIFICATION forming part of Letters Patent No. 740,587, dated October 6, 1903.

Application filed July 15, 1903. Serial No. 165,608. (No model.)

To all whom it may concern:

Be it known that I, HENRY L. PETERS, a citizen of the United States, residing at St. Louis, State of Missouri, have invented certain new and useful Improvements in Window-Screens, of which the following is a full, clear, and exact description, reference being had to the accompanying drawings, forming a part hereof.

My invention has relation to improvements in window-screens; and it consists in the novel construction of screen more fully set forth in the specification and pointed out in the claim.

In the drawings, Figure 1 is an inside elevation of a window-frame, showing my invention applied to the lower window-sash. Fig. 2 is a transverse section on line 2 2 of Fig. 3. Fig. 3 is a cross-section on line 3 3 of Fig. 1, taken through the frame and portion of the wire-netting. Fig. 4 is an enlarged elevation of the fastening device for the screen. Fig. 5 is a cross-section on line 5 5 of Fig. 4. Fig. 6 is an end view of the casing in which the roller carrying the wire-netting is mounted. Fig. 7 is an inside view of the casing, and Fig. 8 is a view of the opposite end of the casing.

The object of my invention is to construct a screen which can be secured at one end to the window-sash, the opposite end of the screen being fastened to a roller at the bases (or top) of the window-frame, the object being to draw the screen after it with each opening of the sash, the roller automatically winding the screen up as the sash is moved to a closed position. While this feature is not broadly new, the present invention contemplates details which go to make up a simple device, which is cheap and durable, and one readily dismantled when the occasion for further use of the screen does not arise. In detail the invention may be described as follows:

Referring to the drawings, F represents the window-frame, and S the lower sash thereof. At the base of the frame is secured a casing composed of a curved body portion 1 and terminal triangular heads 2 2', the former receiving the square end 3 of a spring-roller R and the latter receiving the rounded spindle or stem 3', as is well understood. In mounting the casing on the frame the notches 4 4,

formed along what constitutes the basal edges of the heads, are passed over the square heads 5 of suitable nails driven into the base of the frame at either end of said base, after which the heads are permanently fastened to the sides of the frame by nails driven through the holes 6 6.

The body of the casing is made, preferably, of metal, the ends thereof being folded about and clenched over the curved edges of the heads, Figs. 6, 7, 8, one of the longitudinal edges of the body being extended into the form of a tongue 7, which is passed through an opening of the head and bent against the outer face thereof and toward the overlapping terminal edge of the body portion, the opposite longitudinal edge having a similar tongue 8, which is passed through a marginal recess 9 and likewise folded against the overlapping terminal edge of the body portion, Figs. 6, 7, 8. Over the roller R is passed the wire-netting W, the free end of the netting being carried by a transverse strip or bar 10, which operates in the lateral grooves or ways 11 on each side of the frame F. These grooves or ways 11 are also of metal, the front wall of said groove having a basal extension 11' bent over the body of the roller-casing and the rear wall having an extension 11" spanning the rear opening of the casing, whereby additional protection is afforded the roller R against any possible dislodgment of the same. The netting is secured to the sash S by means of hooks 12 passed over the staples 13, carried by the sash, from which they can readily be detached in winter weather.

As the sash is moved up and down of course the screen moves with it, as is obvious. It is apparent, of course, that the device is susceptible of minor changes without departing from the spirit of the invention.

Having described my invention, what I claim is—

In a window-screen, a suitable sash, a casing mounted at the bottom of the window-frame, and composed of terminal triangular heads and a curved body portion having its ends folded over and clenched to the corresponding curved edges of the heads, tongues extended from one of the longitudinal edges of the body portion passed through the heads and folded against the outer faces, of said

heads, marginal recesses formed in the bases of the heads, the opposite longitudinal edges of the body portion having extended tongues passed through said recesses and bent against 5 the outer faces of the heads, notches formed along the bases of the heads and adapted to be passed over the heads of suitable nails driven into the base of the frame, a transverse strip to which the outer end of the net- 10 ting is secured, a spring-roller mounted in

the casing for the winding up of said netting, and lateral grooves or ways for the said strip, substantially as set forth.

In testimony whereof I affix my signature in presence of two witnesses.

HENRY L. PETERS.
